UNITED STATES PATENT OFFICE.

CHARLES FREBORG, OF KANKAKEE, ILLINOIS.

PLAYER-PIANO AND PUMP THEREFOR.

1,267,859.

Specification of Letters Patent. Patented May 28, 1918.

Application filed February 7, 1914. Serial No. 817,145.

To all whom it may concern:

Be it known that I, CHARLES FREBORG, a citizen of the United States, residing at Kankakee, in the county of Kankakee and 5 State of Illinois, have invented certain new and useful Improvements in Player-Pianos and Pumps Therefor, of which the following is a specification.

This invention relates to improvements in 10 player pianos and pumps therefor. It is well known that player pianos of the type known as pneumatically actuated, are subject to a number of defects, among which is the fact that owing to the irregular operation 15 of the actuating means there are fluctuations in the air pressure, which is negative or below atmospheric in the ordinary type, and this in a number of instances results in variations of speed and tone of the 20 music.

My invention aims to overcome this defect as far as possible, by providing a new form 25 of easily operated pump, in conjunction with what I term a vacuum box or storage chamber together with a new and improved arrangement or combination of "vacuum line" ducts communicating with the actuating pneumatics and motor.

My invention aims to maintain this 30 partial vacuum or negative pressure in the vacuum line substantially uniform throughout the same and also aims to provide means which will keep said reduced pressure substantially uniform during the intermittent 35 alternate operation of the foot pedals.

I also provide means for mounting and arranging my improved construction so that the same may be readily swung to position which I term inoperative position for inspection, repair or the like.

My invention further comprises an improved form of foot actuated operating means and in this connection I have provided an improved arrangement and mounting 45 to enable swinging of the pedals and allied mechanism to inoperative position within the lower part of the piano wherein they will be concealed and out of the way.

I further provide, in connection with 50 these features, an improved mechanism to prevent entrance of mice or the like through the slots in the toe-rail provided for the pedal mechanism.

Still another object of my invention is the 55 construction of pumping elements of the cylinder and piston type and their mounting

and use in pianos of the type mentioned, thereby providing a more positive and efficient air exhausting means than that commonly used such as bellows or the like, and 60 my whole construction enables me to make the mechanism much more accessible, reduces the weight thereof and simplifies the construction in general so that I am enabled to present and construct, in a compact form, 65 the required structure,—a great advantage in player pianos.

These and other objects will be fully set forth and described in the following specification and accompanying drawings, in 70 which:

Figure 1 is a front elevation of my player piano construction;

Fig. 2 is a front elevation on an enlarged scale of a portion of the same;

Fig. 3 is a transverse section through a 75 portion of the piano showing a portion of the mechanism;

Fig. 4 is a view similar to Fig. 3 showing 80 pedals and actuating means swung to inoperative position;

Fig. 5 is a detail partially in section of the vacuum box head;

Fig. 6 is a plan view of the same;

Fig. 7 is a detail of the closing means for 85 a pedal tube slot;

Fig. 8 is a vertical section through the same;

Fig. 9 is a section taken along the line 90 9—9 of Fig. 7.

Like numerals refer to like elements throughout the drawings, in which;

10 designates generally the lower front interior of a piano having the base board 11 and toe rail 12. 13 indicates generally the 95 keyboard supported upon the usual legs or pedestals 14. Blocks 15 are carried by the base board 11, as shown for example in Figs. 1, 3 and 4. To these blocks are secured outwardly extending pins 16 on which are fitted the slotted portions 17^a of the pedestals 17, the slotted portions 17^a being located in the bases or feet of these pedestals, the latter being provided with the lugs 17^b adapted to rest on the blocks 15, as shown in Fig. 4. 100 This construction will enable the pedestal 17 to be swung inwardly or outwardly. The pedestals 17 have the outwardly extending shelf portions 17^c from which extend downwardly the arms 17^d, see Fig. 1, and upon 110 each of these shelf portions 17^c are located a pair of cylinders 18. Mounted in each of

the cylinders 18 is a piston 19 adapted to reciprocate therein and provided with the downwardly extending piston rod 19^a secured thereto. A spring 20 is coiled about 5 each of the piston rods 19^a and extends from the lower side of the pistons 19 to the lower portion of the cylinder 18, as shown for example in Fig. 2. The piston rods 19 are of a size permitting their lower portions to extend downwardly of the cylinders 18 and have their lower extremities attached to the upper end of a tape or flexible member 21. The cylinders 18 are each provided with the heads or caps 22 fitting on the upper end 10 thereof and apertured at 22^a. A manifold 23 has the elbow 23^a communicating with the interior of the cylinders 18, being secured or attached to the upper portion of the heads 22, as shown in Fig. 2. A manifold 23 is 15 provided for each pair of these cylinders 18, as will be further described below. The manifolds 23 are flattened on their upper portion and open, as indicated by numeral 23^b. A flap or valve 24 normally rests on 20 the manifold 23 to close the opening 23^b, being slidably mounted upon the screws or studs 25, this flap or valve 24 being preferably constructed of rubber or other flexible material, the action being such that 25 when the pistons 19 are moved upwardly in the cylinder 18, valve 24 will be moved off the manifold to permit exhaust of air from the cylinder and when the pistons are reversed the valve 24 will close the opening 30 23^b to prevent entrance of air therein. Tapes or flexible members 21 each have an end secured upon a pulley or wheel 26, a pair of adjacent pulleys 26 being secured to a common shaft 27 for rotation therewith. These tapes 21 are partially coiled 35 around the respective pulleys 26 and it is obvious that rotation of the latter in the proper direction will operate to draw the pistons 19 downwardly in the cylinder 40 against the action of the springs 20, the latter serving to return the pistons to their 45 upper position when actuating force is removed from the pulleys 26. The shafts 27 are journaled in the supporting legs of the 50 pedestal 17 and a collar 27^a may be applied to said shaft to prevent its longitudinal movement with respect to pedestal member 17. Adjacent one extremity of each shaft 55 27 is located a pulley 28 secured thereto and prevented from moving outwardly thereon by the collar 27^b. A flexible tape or member 30 has one end secured to the pulley wheel 28 and extends partially therearound, its other end being secured to the extremity 31^a 60 of the rod 31. (See Fig. 3.) This rod is reciprocably mounted in a tube 32 which carries at one extremity an elbow 32^a and a spring 32^b extends from and is attached to this elbow 32^a, its other end being secured to the base board or the like of the 65

piano frame, this spring being under tension when in the position shown in Fig. 3. At its other end the tube 32 carries the casing 32^b having the upwardly extending arm or arms 32^c to which are pivotally attached 70 lugs 33^a of a foot pedal 33. The latter has an elbow or arm 33^b extending downwardly into the casing 32^b and pivotally attached to the rod 31, the latter being loosely mounted in the tube 32. It is obvious that oscillation of the pedal 33 downwardly will operate to partially rotate the pulley 28 in the direction of the arrow, (see Fig. 3), operating through the medium of the shaft 27, flexible members 21 and piston rods 19^a to 80 draw downwardly the pistons 19 in their respective cylinders to create a partial vacuum or reduced pressure in the said cylinders. The springs 20 will operate when the pressure on the pedals is removed to return the 85 same, together with the associated mechanism, to the position shown in Fig. 3, which is normal position. The elbow 32^a has a pivotal connection at 32' to the base of the bracket 17, as is clearly shown in Figs. 3 and 90 4. A panel 35 is provided in the lower front of the piano, this panel being provided at its upper portion with the roller 35^a slidably mounted upon a track 36 carried by the keyboard 13 or the like. The 95 usual spring 37 coacts with the portion of this panel 35 to prevent its accidental outward displacement. The track and roller 36—35^a permit sliding of the panel to one side, to permit swinging of pedal 33, tube 100 32, and rod 31 to the position shown in Fig. 4, this movement being assisted by the spring 32^d, the latter serving to hold the mechanism in the position shown in Fig. 4. When in this position the panel may be 105 closed, being easily moved by its mounting upon the track 36. The lower portion of the panel 35 slides between the beads or ribs 12^a on the upper portion of the toe rail 12, as shown in Fig. 4, this connection being 110 comparatively dust and dirt tight.

It will be apparent that the above described construction permits movement of the pedals, etc. to a concealed position so as not to interfere with the operation of the 115 piano without the player.

What I term a vacuum box 40 is secured to the inner side of the side frame member 41, see Fig. 1, there being one of these vacuum boxes on each side of the piano. 120 Each vacuum box 40 is mounted upon a bracket 42 and secured thereby to the frame member 41. A piston 43 is slidably mounted in the vacuum box 40 and is provided with the piston rod 44 extending downwardly therefrom and having one end attached to the spring 45 which in turn has its other end secured to the base board or bottom 11 of the piano, the spring 45 being arranged to resist upward movement of the 130

piston 43, and also normally to return to its lowered position. The cylinder 40 is provided with the head 46 detachably secured to its upper portion, this head being internally chambered, as indicated by numeral 46^a and having its lower wall 46^b apertured, as indicated by numeral 46^c, the wall 46^b comprising, in effect, a partition between the chambers 46^a and the interior of the vacuum box 40, the apertures 46^c extending between. A central boss 46^d is provided in the head 46 and is centrally apertured to permit the insertion of a duct 47 to communicate with the interior of the box 40. A second duct 48 extends through the aperture 46^e in the head 46, the same extending from the chamber 46^a outwardly of the head 46. The duct 48 extends to and communicates with the manifold 23, as shown in Fig. 2. A flap or valve 49 rests on the upper side of partition 46^b and is fitted loosely around the boss 46^d, this flap 49 being of slightly less diameter than the diameter of the outer wall of chamber 46^a, as shown for example in Figs. 5 and 6. The flap 49 being formed of rubber or other flexible material and normally resting upon the studs or flanges 46^f of the partition 46^b, will operate to prevent flow of air from the duct 48 into cylinder or box 40, although permitting flow from the latter to the former. The duct 47 extends upwardly in the piano and is in communication with a cross duct 50, this latter extending across between and communicating with the two ducts 47, as shown clearly in Fig. 1.

A motor 51 provided with the intake duct 52, is supported, as shown by the duct 50, and communicates through the said duct 52 therewith. A plurality of tubes 53 also extend across between the ducts 47 and are in communication therewith, these tubes 53 being apertured to communicate with, and arranged to adjustably support actuating pneumatics 54.

It will be apparent, in the operation of my device, that when the pedals 33 are intermittently and alternately depressed and released, the mechanism described herein, will operate to intermittently and alternately depress each pair of adjacent pistons 19 in the cylinders 18. When the pair of pistons shown in Fig. 2, for example, is depressed against the action of the springs 20, the air will be exhausted through apertures 46^c from the vacuum box 40 and from the duct 47, the latter serving to transmit the resultant partial vacuum or section to the entire vacuum line, as I term it, comprising ducts 47, cross duct 50 and cross tubes or ducts 53. At the same time this exhausting of the air from vacuum box 40 is considerably greater than the amount of air ordinarily drawn in through the duct 47, this difference depending, of course, on the speed of play-

ing the piano, the sheet of music being played, and other similar conditions. Owing to this excess of negative pressure obtaining in the box 40, the piston 43 will be drawn upwardly therein against the action of the spring 45, the tension of which will be increased. The size of the vacuum box 40 having been properly determined, in relation to the capacity of the pumping members 18 and the negative pressure which it is necessary to create in the line, there is no danger that piston 43 will be drawn to its uppermost position in the ordinary operation of the piano. When the corresponding foot pedal has been depressed to its lowest limit and released, the springs 20 will operate to return the same, as explained above, to normal position at the same time raising the pistons 19 in the cylinders 18 to the position shown, this upper limit being determined by the size of the springs 20 and nuts or collars 20^a secured to the piston rods 19^a exteriorly of the cylinders 18. The air drawn into the cylinders 18 on the previous stroke is expelled through the opening 23^b in manifold 23 on the up-stroke, valve 24 being raised off its seat to permit such exhausting. The valve 49 will prevent flow of air on this up-stroke, back into the vacuum box 40, as was explained above. While the pistons are making their up-strokes on this side of the piano, the pressure in the vacuum line would be wholly dependent on that produced by the other pair of pumps 18, or their equivalent, and the resulting operation would be pulsating and intermittent were it not for the piston 43 in the vacuum box 40, this piston 43, as will be apparent, acting as an accumulator or the like to store up the partial pressure or vacuum produced in the box 40 by the previous down-stroke of the pistons 19, since, at the completion of this down-stroke, the vacuum or negative pressure in the line will be maintained by the movement of the piston 43 downwardly in the box 40 through the medium of spring 45. Inasmuch as both pairs of pumps and both vacuum boxes 40 operate in the same manner, except that ordinarily they are alternately actuated, it is not necessary to describe in detail the operation of both sets. It is to be noted, however, that in the event, for example, a greater pumping effort is produced by one side, the cross communication through duct 50 and tubes 53 between ducts 47 and vacuum boxes 40, will result in the maintenance of a comparatively uniform or balanced pressure in the line, as will be apparent, so that it will be apparent that I have provided means for producing substantially constant negative pressure in the line and also means for balancing the pressure to enhance the maintenance of the uniform vacuum. When the pedals and tubes 32 are in the operative position shown in

Fig. 3, the extremities of the tubes 32 rest in slots 12^a in the toe rail 12, see Fig. 8. Were these slots unprotected, when the pedals are swung to inoperative position, as shown in Fig. 4, holes would be left which would permit the entrance of mice or the like, a disadvantage common to many pianos and players in present use and to prevent this I have provided the construction shown in Figs. 7, 8 and 9. A follower or cap 60 is provided with the downwardly extending front flange 60^a and angularly disposed top flange 60^b. A stud or pin 60^c extends downwardly from the flange 60^b and is slotted, as indicated by numeral 60^d. This pin or stud 60^c is slidably mounted in the tube 60^e carried in the toe rail 12, the lower end of the latter being provided with the plug 60^f centrally apertured at 60^g, a seat being provided in the plug for the ball 60^h which normally closes the opening 60^g, this being provided to permit entrance of air to the tube 60^e to prevent a vacuum forming therein which would interfere with the operation of this device.

A spring 60ⁱ is located in the tube 60^e and extends between the lower portion of the pin 60^c and plug 60^f operating normally to maintain the follower 60 in the position shown in Figs. 7 and 9 wherein it closes the slot 12^a. When the pedals are moved to their operative position, as shown in Fig. 3, the tubes 31 will operate to depress follower 60, as shown in Fig. 8.

As mentioned above, the hinged or pivotal mounting of the pumps and supporting structure will permit outward swinging of the pump apparatus, when so desired, the duct 48 being detachable to permit such movement. Inasmuch as this movement is not necessary except in case of some breakdown or the like, I desire to rigidly support the pump mechanism in operative position, and to accomplish this purpose I select the upper end of bracket arm 17 by screws or the like to the block 61 carried by the keyboard or the like of the piano, see Fig. 2.

It is believed that the above description is sufficient to enable those skilled in the art to understand the construction and operation of my device without further amplification. It is obvious that the structure set forth in the specification and shown in the drawings is susceptible of many modifications and improvements, and I do not wish to be restricted to the description or showing beyond the scope of the appended claims.

I claim—

1. In combination, a pair of foot actuated air exhausting means, a vacuum box communicating with each of said means, duct members communicating with each of said boxes, tubes across between and in communication with said first named ducts, ac-

tuating pneumatics secured to and in communication with said last named tubes, another tube extending between and in communication with said first named ducts, and a motor supported by and in communication with said last named tube. 70

2. In a device of the class described, a pump comprising a cylinder, a piston reciprocably mounted in said cylinder, a piston rod secured to said piston and extending outside of said cylinder, foot actuated means to move said piston in one direction, and independent positive means to return said piston to position. 75

3. In a device of the class described, a plurality of cylinders, pistons reciprocably mounted in said cylinders and having piston rods secured thereto and extending outside of said cylinders, means to move said pistons independently of each other in one direction, and means to independently return either of said pistons after such movement. 80

4. In a device of the class described, a pump comprising a cylinder, a piston reciprocably mounted in said cylinder, a piston rod secured to said piston and extending through the end of said cylinder, means to move said piston in one direction in said cylinder, and means to return said piston 95 after such movement, said last named means comprising a spring. 90

5. In a device of the class described, a pump member comprising a cylinder, a piston reciprocably mounted in said cylinder, 100 a rotatable pulley or the like, a flexible member connecting said piston to said pulley, and means to rotate the latter to actuate said pump.

6. In a device of the class described, a pump comprising a cylinder, a piston reciprocably mounted in said cylinder, a piston rod secured thereto, a pulley member, means to rotate said pulley, and a flexible tape secured to said pulley and to said piston rod whereby rotation of said pulley in the proper direction will operate to move 110 said piston. 105

7. In a device of the class described, a pump comprising a cylinder, a piston reciprocably mounted in said cylinder, a piston rod secured thereto, a pulley member, means to rotate said pulley, a flexible tape secured to said pulley and to said piston rod whereby rotation of said pulley in the proper direction will operate to move said piston, and means to return said piston in the opposite direction after such movement. 120

8. In a device of the class described a pump comprising a cylinder, a piston reciprocably mounted in said cylinder, a piston rod secured thereto, a pulley member, means to rotate said pulley, a flexible tape secured to said pulley and to said piston rod whereby rotation of said pulley in the 130

proper direction will operate to move said piston, and means to return said piston in the opposite direction after such movement, said means comprising a spring.

- 5 9. In a device of the class described, a pump comprising a cylinder, a piston reciprocably mounted therein, a rotatable pulley, a flexible member connecting said piston to said pulley, means to rotate said pulley, said means comprising a foot actuated member, a second pulley, and a flexible member operatively connecting said foot member to said second pulley.
- 10 10. In a device of the class described, a pump comprising a cylinder, a piston reciprocably mounted therein, a rotatable pulley, a flexible member connecting said piston to said pulley, means to rotate said pulley, said means comprising a foot actuated member, a second pulley, and a flexible member operatively connecting said foot member to said second pulley.

- 15 11. In a device of the class described, a pump comprising a cylinder, a piston reciprocably mounted therein, a rotatable pulley, a flexible member connecting said piston to said pulley, means to rotate said pulley, said means comprising a foot actuated member, a second pulley, and a flexible member operatively connecting said foot member to said second pulley, both said pulleys being mounted upon a shaft whereby rotation of said last named pulley will operate to rotate said first-named pulley, and vice versa.
- 20 12. In a device of the class described, an air exhausting means, actuating means to operate said air exhausting means, said actuating means comprising a foot actuated member, a rotatable shaft, and a flexible member operatively connecting said foot actuated member to said shaft.
- 25 13. In a device of the class described, an air exhausting means, means to actuate the same, means to actuate said last named means comprising a foot pedal, a rotatable shaft, a connecting rod pivotally connected to said pedal, and a flexible member opera-

- 30 40 14. In a device of the class described, an air exhausting means, means to actuate the same, means to actuate said last named means comprising a foot pedal, a rotatable shaft, a connecting rod pivotally connected to said pedal, and a flexible member opera-
- 45 15. In a device of the class described, a rotatable shaft, a pulley mounted upon said shaft, a flexible member having one end secured to said pulley adapted to wind upon the same, a rod, a pedal, said rod being pivotally connected to said pedal and to said flexible member.

- 50 16. In a device of the class described, a rotatable shaft, a pulley mounted upon said shaft, a flexible member having one end secured to said pulley adapted to wind upon the same, a rod, a pedal, said rod being pivotally connected to said pedal and to said flexible member, and a tube, said rod being reciprocably mounted in said tube.

- 55 17. In a device of the class described, a rotatable shaft, a pulley mounted upon said shaft, a flexible member having one end secured to said pulley adapted to wind upon the same, a rod, a pedal, said rod being pivotally connected to said pedal and to said flexible member, a tube, said rod being reciprocably mounted in said tube, and a sup-

porting web or bracket secured to said tube, said pedal being pivotally mounted on said bracket.

18. In a device of the class described, pumping means, means to actuate said pumping means comprising a reciprocating rod, a tube, said rod being reciprocably mounted in said tube, a pedal operatively connected to said rod, means to pivotally support said pedal, said means being secured to said tube, means carried by said tube adjacent one end thereof, said means being pivotally mounted, whereby said pedal, tube and rod may be moved to operative or inoperative position.

19. In a device of the class described, pumping means, means to actuate said pumping means comprising a reciprocating rod, a tube, said rod being reciprocably mounted in said tube, a pedal operatively connected to said rod, means to pivotally support said pedal, said means being secured to said tube, means carried by said tube adjacent one end thereof, said means being pivotally mounted, whereby said pedal, tube and rod may be moved to operative from inoperative position, and vice versa, and a spring extending from said last named means to and secured to said piano, said spring being adapted to hold said pedal, tube and rod in inoperative position.

20. In a device of the class described, having a toe rail, said rail being slotted, a foot actuated means extending through said slot when in operative position and located outwardly of said slot when in inoperative position, and means to automatically close said slot when said actuating means is moved therefrom to prevent entrance of mice or the like through said slot.

21. In a device of the class described, having a toe rail, said rail being slotted, a foot actuated means extending through said slot when in operative position and located outwardly of said slot when in inoperative position, means to automatically close said slot when said actuating means is moved therefrom to prevent entrance of mice or the like through said slot, said means comprising a follower slidably mounted in said slot, and means to normally move said follower to position closing said slot, said means comprising a rod secured to said follower and a spring coacting therewith.

22. In a device of the class described, having a toe rail, said rail being slotted, a foot actuated means extending through said slot when in operative position and located outwardly of said slot when in inoperative position, means to automatically close said slot when said actuating means is moved therefrom to prevent entrance of mice or the like through said slot, said means comprising a follower slidably mounted in said slot, means to normally move said follower to position closing said slot, said means comprising a rod secured to said follower, a

spring coacting therewith, said rod and spring being mounted in an aperture in said toe rail, said aperture being normally closed at one end, and means to permit ingress of air thereto.

21. In a device of the class described, a pumping member, a vacuum box in communication therewith, said pumping member being arranged to exhaust the air from 10 said vacuum box, and thereby reduce the pressure in the same, and means coacting with said box to maintain said reduced pressure therein.

22. In a device of the class described, a 15 pump comprising a cylinder, a piston reciprocably mounted therein, means to reciprocate said piston in said cylinder, a vacuum box, a duct connecting said pump and said vacuum box, and means to permit withdrawal of said air from said box by said 20 pump and to prevent passage of air from said pump to said vacuum box.

23. In combination, a pumping member 25 comprising a plurality of cylinders, pistons reciprocably mounted in said cylinders, a manifold connecting said cylinders, and means to permit outflow of air from said cylinders when said pistons are actuated in one direction, said means being adapted to 30 prevent entrance of air therethrough when said pistons are moved in the opposite direction.

24. In combination with a piano or the like, a pumping member located in the lower 35 portion thereof, a frame, said pump being carried by said frame, said frame being hingedly mounted to move bodily outward with said pumping member when so desired.

25. In combination with a piano or the 40 like, a pumping member located in the lower portion thereof, a frame, said pump being carried by said frame, said frame being provided with pedestal portions pivotally attached to the frame of said piano whereby 45 said frame and pumping member may be hingedly swung outwardly of said piano.

26. In combination with a piano or the like, a pumping member located in the lower portion thereof, a frame, said pump being carried by said frame, said frame being provided with pedestal portions pivotally attached to the frame of said piano whereby 50 said frame and pumping member may be hingedly swung outwardly of said piano, said frame being provided with an arm adapted to be secured to said piano frame 55 when in operative position.

27. In a device of the class described, an air exhausting means, a vacuum box, a duct connecting said air exhausting means with 60 said vacuum box, a partition in said box separating the main portion of the latter from said duct, said partition being apertured, and a valve normally resting on said partition and adapted to close said aperture. 65

28. In combination, an air pump, a vacuum box, a duct connecting said vacuum box with said air pump, said vacuum box being provided with a partition therein, said partition being apertured, and means to close 70 said aperture to prevent flow of air from said pump to said box, said means being arranged to permit exhausting of air from said box by said pump, and a second duct 75 communicating with the interior of said box through said partition.

29. In combination with a pumping means, a vacuum box and a vacuum line, said box being provided with a head, said head being 80 apertured to communicate with said box, a duct leading from said head to said pumping means whereby air may be exhausted through said apertured head from said box to said pumping means, means to prevent 85 reverse flow to said box, and a second duct leading through said head and communicating with said box.

30. In combination with a pumping means, a vacuum box and a vacuum line, said box 90 being provided with a head, said head being apertured to communicate with said box, a duct leading from said head to said pumping means whereby air may be exhausted through said apertured head from said box 95 to said pumping means, means to prevent reverse flow to said box, a second duct leading through said head and communicating with said box, a piston slidably mounted in said box and arranged to be moved in one 100 direction when the air is exhausted from said box, and means coacting with said piston to resist such movement and to normally return the same in a reverse direction after such movement whereby air will be 105 drawn into said box through said second named duct.

In testimony whereof, I have subscribed my name.

CHARLES FREBORG.
